UNITED STATES PATENT OFFICE.

WALTER B. JOURDAN AND JONATHAN A. HUNT, OF WESTBOROUGH, MASSACHUSETTS, ASSIGNORS TO THE HUNT MANUFACTURING COMPANY, OF SAME PLACE.

DESIGN FOR A SADDLE-SEAT.

SPECIFICATION forming part of Design No. 22,713, dated August 15, 1893.

Application filed June 22, 1893. Serial No. 478,518. Term of patent 14 years.

To all whom it may concern:

Be it known that we, WALTER B. JOURDAN and JONATHAN A. HUNT, both citizens of the United States, residing at Westborough, in 5 the county of Worcester and State of Massachusetts, have jointly invented and produced a new and original Design for Bicycle Saddle-Seats, of which the following is a specification, reference being had to the accompanying drawings, forming a part thereof.

Our invention relates to saddle seats for bicycles, &c., and more particularly to the saddle seat ordinarily made of leather, and the object of our invention is to produce a seat 15 of novel and attractive design.

Our invention consists in our new and original design for saddle seats for bicycles, &c., as will be hereinafter fully described.

Referring to the drawings: Figure 1 is a 20 perspective view of a saddle seat, showing our design. Fig. 2 is plan view of the seat shown in Fig. 1.

In our design for saddle seats for bicycles, &c., the top of the saddle seat does not have

a plain appearance, but shows a pattern or 25 configuration, comprising straight lines and curved lines, extending from the front of the saddle seat to nearly the rear edge thereof.

In the accompanying drawings, 1 is a saddle seat of our design for bicycles, &c., and 2 30 are holes or openings extending through the central portion thereof.

3 is the pattern line extending from the front end of the seat nearly to the rear end thereof, in straight and curved lines along 35 the top of the seat, with two scrolls or loops 3' on the rear widened surface of the seat. A pattern line 4 also extends around the lower edge of the seat, as shown in Fig. 1.

What we claim is—

The design for saddle seats for bicycles, &c., substantially as shown and described.

WALTER B. JOURDAN.
JONATHAN A. HUNT.
